UNITED STATES PATENT OFFICE.

JAMES J. FITZ PATRICK, OF MARBLEHEAD, AND RALPH T. CHEESEMAN, OF LYNN,
MASSACHUSETTS, ASSIGNEES TO GENERAL ELECTRIC COMPANY, A CORPORATION
OF NEW YORK.

RECTIFYING ARC DEVICE.

Application filed March 11, 1925. Serial No. 14,801.

The present invention relates to the construction of electric rectifiers in which an arc-like discharge in a gas is utilized which operates between a cathode operating at 5 incandescence and an anode which is maintained relatively cool. It is the object of our invention to increase the efficiency and uniformity of this class of devices.

Heretofore, it has been the practice to 10 seal the electric terminals for the electrodes into opposite necks or arms of a bulb. This construction rendered it impracticable to space apart the electrodes an exactly predetermined distance and required separate 15 attachment of the external current conductors to the terminals when the bulb is inserted in its outfit.

In accordance with our invention the cathode and the anode are sealed into a 20 stem projecting into the neck of the bulb and are spaced apart a distance not materially greater than the arc gap between the electrodes. By using this construction the gap between the electrodes can be accurately gauged prior to sealing the stem into the bulb and thereby the best operating 25 conditions can be secured. The size of the bulb can be decreased by this construction and contact members can be provided which 30 are connected by a single operation, such as screwing the bulb into a socket similar to the insertion of an incandescent lamp into its socket. The novel features of our invention are set forth with greater particularity 35 by the appended claim.

The accompanying drawing shows in Fig. 1 a vertical sectional view of our improved rectifier bulb; Fig. 2 shows in perspective an outfit in which the bulb is mounted in a 40 socket in suitable relation to a transformer and auxiliary devices, part of the wall being shown broken away; and Fig. 3 is a diagram of circuit connections.

Referring to the drawing, the rectifier 45 device as shown in Fig. 1 comprises a bulb 1 having a neck 2 in which is sealed a glass stem or press 3, and containing a gas at substantial pressure. The cathode leading-in conductors 4, 5, and the anode conductor 6 are sealed by fusion into this stem and

extend side by side into the bulb. No discharge occurs between the cathode and anode conductors under normal operating conditions.

The cathode conductors 4, 5 are terminated by a filamentary spiral cathode 7, preferably consisting of tungsten. The conductor 6 is terminated by a disc-shaped anode 8 consisting of suitable conducting material, such as nickel, molybdenum, tungsten or graphite. The cathode conductors 4, 5 are joined electrically to the members 9, 9' of a screw base and the anode conductor 6 is joined electrically to a metal ring 10 encircling the neck of the bulb just above the screw base.

In the manufacture of the bulb the operator first mounts the electrodes on the stem 3 and gauges the spacing between the cathode and the anode to a distance which has been found to give the desired operating characteristic.

These characteristics, such as starting voltage and consumption voltage, may be altered within limits for a given device by 75 altering the distance between the electrodes. The present construction, which permits accurate spacing, promotes the production of devices of uniformly high efficiency.

The described form of rectifier bulb is 80 well adapted for insertion into an outfit such as shown in Fig. 2. This outfit comprises a sheet metal container 11 having mounted in its base the core 12 of a transformer having windings 13, 14. Mounted upon the side wall of the container is a socket 15 (shown partly broken away) into which the rectifier bulb may be screwed as shown in Fig. 3. The members 16, 17 of the base are connected by the conductors 18, 19 to a section 14 of the secondary winding of the transformer whereby the cathode is furnished with heating current. The ring 10 is connected by a spring contact 20 to the negative terminal 21 of the apparatus.

When a battery 22 is to be charged it is connected either to the positive terminals 23, 24 or 25, depending on the voltage desired. A resistance 26 is included in circuit with the positive tap or circuit 24 whereby 100

the direct current voltage is reduced for charging a battery of lower voltage. The high voltage tap 25 contains an incandescent lamp 27 which is mounted in a socket 28 affixed to the outside wall of the container. This relatively high voltage tap is adapted for charging high voltage storage batteries for radio outfits.

The sliding contact between the ring 10 and the spring pressed terminal 20 is adapted to carry relatively large currents without arcing difficulties as it readily maintains itself in positive conducting relation.

What we claim as new and desire to secure by Letters Patent of the United States, is:

A rectifier comprising a glass bulb having a neck which terminates in a stem, a filamentary cathode and a cooperating anode positioned in said bulb, conductors for the filament and anode sealed into said stem, a screw base secured to the stem and provided with contacts which are connected to the filament conductors, a metallic band-shaped member encircling said neck and spaced therefrom by insulating material and a connection between said member and the anode conductor.

In witness whereof, we have hereunto set our hands this ninth day of March, 1925.

JAMES J. FITZ PATRICK.
RALPH T. CHEESEMAN.
